FOAM REMOVER

Ehrhart J. Kurtzbein, St. Paul, Minn.

Application October 14, 1938, Serial No. 234,967

4 Claims. (Cl. 225—8)

My invention relates to foam removing devices useful particularly where beverages are sold for immediate consumption. It is well known that various ales or beverages when tapped, as 5 into a glass, produce quantities of foam at the top and besides causing a slow filling of a glass make necessary certain devices for removing the foam, such means hitherto used producing undesirable conditions such as foam on the bar and 10 drain-board and on the exterior of the container used.

My device is designed particularly for the purpose of eliminating the objectionable conditions stated and the main object is to provide a simple 15 highly efficient and inexpensive foam remover as hereinafter fully described and illustrated in the accompanying drawing, in which—

Fig. 1 is a vertical sectional elevation of my improved foam removing device showing a preferred 20 construction. Fig. 2 is a front elevation of Fig. 1. Figs. 3 and 4 are, respectively, a side and a front elevation of a modified form of the foam remover without a motor. Figs. 5 and 6 are modifications 25 of Fig. 1, in reduced scale, omitting the base parts, but showing the motor and its fan in modified mounting, horizontally, and in vertical positions respectively.

Referring to the drawing by reference numerals, like characters designating corresponding 30 parts in the various views, 5 designates a bar such as used in beverage and ale dispensing places, part of said bar comprising a grate 5A (Fig. 1) for drainage and located under any type of tap used for filling various types of containers such as a glass 6.

My device comprises an upright, inverted L-shaped standard of which 7 is the vertical part with a flat or flanged base 7F and adapted to be fixed rigidly as with screws 8 to the top of a 40 bar 5. The horizontal arm 7A of the standard projects toward the back of the bar and is a rigid arm extending in spaced relation over the bar a predetermined distance, usually about eight inches.

In the electrically operated form of my device, 45 at the convergence of the vertical and horizontal arms of the standard it is formed with a preferably cylindrical frame 9 open rearwardly and in which may be fixed an electric motor 10 having any suitable type of electric control, as the circuit 11 with switch 12.

The forwardly directed or projecting motor shaft 10S carries a multiblade fan 11 rotatable within a housing 7H comprising an integral part 50 of the standard, said housing below the fan com-

prising a downwardly directed duct 7H' opening downwardly at 21 just over the drainboard 5A of the bar.

In Figs. 1 and 2, arm 7A comprises a forwardly and downwardly tapering member the outer part 5 of which comprises a downwardly open elongated nozzle 13 with a horizontal lower face 14. Or said nozzle may be designated as an elongated downwardly open duct (in horizontal place) said duct upwardly and inwardly of the face 14 comprising 10 a rearwardly flared duct 15 communicating directly with the housing 7H and concentrically of the fan 11.

In the non-electric form of my device (Figs. 3 and 4) the horizontal arm 7A comprises in part 15 a vertically fixed blade 13B with a horizontal lower edge 14 corresponding to lower edge 14 of member 13 in Fig. 1.

This device is mounted in proximity to any 20 beer tap or the like, and when a quantity of foam accumulates in a glass the latter is merely held, by attendant, in the position shown in Fig. 1 directly under the nozzle 13 and passes the glass by the nozzle in horizontal direction. Assuming 25 that the electric fan or propeller 11 is rotating, the foam will be quickly and efficiently drawn off from the glass through duct 15 to housing 7H without disturbing the heavier liquid contents of the glass 6.

It will of course be readily understood that the 30 rotary action of fan 11 generates suction in the duct 15 and which will carry the foam quickly into the housing 7H and within said housing the fan will disintegrate the foam by its centrifugal action which will cause the foam to be reduced 35 to liquid particles which subsequently will gravitate in the tube 7H' and discharge at 21.

23 is a fine mesh screen mounted within the housing 7H at the inner end of duct 15 and so positioned in the path of suction that the foam 40 will be broken up before reaching the fan and any liquid particles on said screen may drip directly into the duct 7H'.

In the purely mechanical form of my device 45 illustrated in Figs. 3 and 4, the beverage glass is contacted with and passed under the blade edge 14, which action scrapes off all protruding foam. Any foam adhering to the blade is removed by a pair of pivotally mounted sponge-rubber pads 16 one at each side of the blade 13B.

Both pads 16 are held normally spaced from the blade, each by a pair of arms 17 fixed at their upper extremities each pair on a rotatable shaft 18 mounted parallel to and adjacent the side of the blade arm 7A. Externally of the free 50

end of arm 7A, said shafts are provided with a pair of meshing gears 19 (one fixed on each shaft) and one of said shafts further provided with a turning key 20. By manipulating this key both shafts may be oscillated simultaneously to swing the pads downwardly into contact with the sides of the wiper blade, as to position shown in full lines in Fig. 4. The pads are normally and yieldably impelled outwardly from the blade (as dotted line positions shown in Fig. 4) by means of a coil spring 22 on either or both of the shafts 18.

Obviously the absorbent pads are manipulated against the sides of the blade against the spring action, such contact of the blade surface being to remove the foam from the sides of the blade by pressure against the sides thereof. Squeezing action against the blade will liquefy some of the foam and which will drip off and some of the foam will adhere to the pads when they are retracted to their outer positions in which they may continue to drip or the pads may be removed at intervals for cleaning.

Modifications may be made as in Figs. 5 and 6, in the upper portion (as in Fig. 5) the stand being shown with a semi-hollow motor retaining head part to hold the motor in horizontal plane, nozzle 13 being flared upwardly and leading into a circular chamber 7C around the fan and forward part of the motor, the duct 7H' extending down directly under the motor. In Fig. 6 the motor and its shaft are vertically disposed, the upper part of the pedestal or stand having a seat 7S for the motor, and instead of a tapered nozzle a horizontal housing 25 integral of the head encloses the fan 11 which is positioned directly over an aperture in said housing and having a screen 26. The interior of housing 25 communicates directly with the outlet or drain duct 7H'. Other modifications of construction may be embodied, within the scope of the above description and the following claims, without departing from the scope and spirit of my invention.

I claim:

1. A foam removing device comprising an inverted L-shaped standard and the horizontal arm thereof in fixed vertical relation over the base, said arm comprising in part a fixed blade with a

horizontal lower edge and means adjacent said edge for catching and removing foam from the upper and open part of a container passed horizontally under said edge of the blade.

2. The structure specified in claim 1, and a rotary motor mounted in said standard, a fan on the shaft of said motor, a part of said standard comprising a housing about said fan and an outlet of said housing extending integrally thereof below said fan, the horizontal arm of said standard extending outwardly from the fan housing and formed with a duct communicating with said fan housing at one end and its other end comprising an elongated slotted opening directed downwardly at said lower edge of the blade, said fan arranged to generate suction through said duct, as shown and described.

3. The structure specified in claim 1, and a rotary motor mounted in said standard, a fan on the motor shaft, a part of said standard comprising a housing about said fan and a downward extension of said housing comprising an outlet duct, the horizontal arm of said standard extending outwardly from the fan housing and formed with a duct communicating with said fan housing at one end and its other end comprising an elongated slotted opening directed downwardly at said lower edge of the blade, said fan arranged to generate suction through said duct, and a screen fixed in said fan housing intermediate said fan and the adjacent inner terminus of said duct.

4. A foam removing device for beverage containers, said device comprising an inverted L-shaped standard adapted to be fixed on a flat surface, a fixed wiper blade in vertical plane and extending downwardly from the horizontal arm of the standard, the lower edge of said blade in horizontal plane, foam engaging and removing means comprising an elongated pad of porous material and pivotally mounted one at each side of the said blade, and spring actuated means holding the said pads normally away from the blade and means for actuating said pads to move simultaneously into contacting positions with the blade, substantially as shown and described.

EHRHART J. KURTZBEIN.
